(54) **MORTISING & BORING MACHINE**

(76) Inventor: **George Page**

George Page of Keene, New Hampshire,
Sells Patent (Patented March 15, 1856)

This is to certify that I have sold to George Page of Keene, New Hampshire, a new and useful improvement in the method of mortising by a machine, which machine is described as follows:—

The bottom consists of two pieces of elm wood, four inches wide, three inches thick, one piece three feet long, the other piece three feet and four inches, these are bolted together enclosing each other at right angles, the plane of intersection in the horizontal piece being at equal distances from each end and in the longest piece about two feet from one end, the short end being at the fore end of the machine. At the place of intersection a mortise is made into which by a tenon is fixed an upright post four inches wide and three inches thick, and seven inches high from the bottom of the dill, beginning at three inches from the top of the dill, a mortise is made in the side of the longest dill through this post one inch wide and eleven inches long. Into the end of this post behind the post is fixed by mortise and tenon an upright post four inches wide and three inches thick and seven inches high from the bottom of the dill, at the top of this post one end of a bar is inserted, a post passing through the post and end of the bar, a socket box passes through the center of the post and has a pin through the end of a piece of broad iron which is placed flatfoot, six inches above the crook, into the post and this is made thin at the same division, four eighths of an inch wide and five eighths inches long, this thin metal plate has two small iron bolts with a small collar and nut on one end of each, one of these bolts passing thro' a piece of iron called a Rod and has a head on that end, this the other

end of the post that a hole is made at the which passes, and is in the shape of a segment of a circle, each end of which is attached to the lower side of the post. This is in proportion to two & a half feet long, & four inches broad at one. By means of two bolts, screws, &c. The post may be made fast and steady at any desired height or inclination. A board three inches and a half wide is let into the post, even with the face of it and crossing it, the upper edge being two inches above the top of the mortise the board being cut away against the mortise. Near the top of the board a slot or piece of iron is bored firmly to the post to prevent the timber from moving by the operation of the machine. About four feet three inches, from the bottom of the post a brace of the size of the post and three feet long is inserted in the post inclining forward at an angle of sixty two degrees from a horizontal line. This brace is made steady by a girder or iron rod with a screw and nut one end and a head on the other passing through it and the post near the top of the latter. Beginning five feet nine inches from the bottom of the post and continuing up the post, in the same direction as those below, an inch wide and eight inches long. A similar mortise level with this is made thro' the brace. To the outside of the brace below the mortise is fastened ^{by means of} a piece of cast iron shaped thus & having a horizontal hole thro' the projecting ends. This by means of two flat pieces of iron eight or ten inches long is connected with the end of a iron which passes thro' the mortise in the brace and post, and is about two feet nine inches long. Back of the post several holes are made horizontally thro' the post and corresponding holes thro' the brace fastened on board. A rod with a clevis at each end connects the two braces, the pin being placed thro' each of the holes, so will give the purchase and motion wanted. The end of a spring made of hickory rods, or other elastic timber is inserted in a mortise near the top of the brace and passing over the top of the post is

connected with the upper cover at the end by a leather strap having a buckle by which it may be lightened or fastened at pleasure. The important part of the machine, is a slide which is a rod of iron four inches round, seven eighths of an inch in diameter and two feet six inches long. Into the lower end a hole is drilled longitudinally two inches deep to receive a rivet for the shield. (About two inches from the lower end) a hole is made one and a half an inch long and of the same diameter the sides of which are made flat by which the shield may be keyed or driven in. (About two inches from the lower end on one side is a small hole, also drilled through it, and from and a half inches above and down into which is inserted and fastened the head end of a square iron guide. Into the top of the slide a hole is also drilled two inches deep into which a bolt is inserted and fastened by a pin. This bolt has a head shaped like half a globe or half the top being round. Being with pins projecting at opposite sides called a yoke; second, the bolt between the head and the hole the pins going thro' the ends, of a lever which passes over the upper cover and the post. To the lower side of this lever is fastened an iron plate, into which a hole is made to receive the head of the bolt, which is drawn up into it by a wedge driven between the upper side of the lever and the bolt. About two inches below this lever the slide passes through a board shaped thus . The projection is inserted in a hole thro' the post. (Against this hole on the left side a mortise is made into the end and a small hole is bored to the mortise from the right side. (A hole being cut across with an eye on one end and a thumb hole on the other is introduced into the mortise and holes. The projection of the bar passing through the eye. By means of this the slide may be taken at any desired distance from the post. The slide then passes down through a hole in the brace and a long bar sixteen inches above the lower end of the slide of square, then another bar one hundred and four inches long and is made of cast iron. One part is shaped thus and the other thus . The length of the large or pin from a to b, is about six inches, the ground thickness being smoothly planed, with a projection rising at the edges, a and b. The part c, is

is inserted in a hole thro' the foot, and made fast in the same way as the upper box before described. The smaller piece is the same thickness, a little shorter and is connected with the larger ^{box} ~~box~~ so that the two half circles form a hole or box an inch and a quarter in diameter. Within this, and inside box, the hole thro' which is, soon right of an inch in diameter, being the same as that of the slide. It has a perpendicular groove cut on one side, ^{inside} for the quiver wire to guide it to run in. It is an inch and a half long and has a groove running id on the outside as wide as the two first described parts are thick, and so deep that the feet thus made in them may be received, and turn within the outer box. At the upper end of this inner box on one side, outside is a small projection one fourth of an inch long, round, half an inch in diameter with a hole made into it longitudinally to receive one end of a small spring or latch. By this spring or latch the slide may be turned half round and may be kept steady in place by letting the latch fall into a small groove or notch made in the work, or projections above mentioned. The machine should stand upon the right side of a stud or post and bolted to it, and if convenient a long spring may be used fastened to a joist above instead of the short one attached to the machine. When the machine is to be used the movable rest is adjusted and made fast at the proper place to admit the wood to be worked between the iron and the rest on the foot. The wood to be worked is to be placed on the rest, the chisel being set to cut either side of the wood, the lower lever being forced down by the foot which brings down the upper lever to which the slide is attached and drives the chisel into the wood. The foot being raised the chisel at the top withdraws the chisel from the wood, which is then moved, and the foot applied again, and so on until one end of the wood is finished. By means of this spring or latch, the slide is turned half round, and the other end of the wood is finished by another operation. It is a good method on end of the wood to be secured or turned by means of the segment of a crooked circular brace below the chisel being convenient and not injurious. It can in this manner be used, without fear of attacking the slide to the upper part of the box to the machine, and also it will be found to give a better finish than described.

William Lanson
